(57) **CLAIM**

The ornamental design for a food wrapping paper, as shown and described.

DESCRIPTION

FIG. 1 is a front view of a food wrapping paper showing my new design;

FIG. 2 is a rear view thereof;

FIG. 3 is a front view showing the food wrapping paper folded along a centerline; and,

FIG. 4 is a rear view thereof.

The broken lines in FIGS. 1 and 3-4 represent folding lines showing the fold position of the food wrapping paper and form part of claimed design.

The arrows in FIGS. 1 and 3-4 indicate alignment positions and form part of claimed design.

The black rectangles in FIGS. 1 and 3-4 indicate the position to press when the food wrapping paper is folded along the folding lines and form part of claimed design.
